UNITED STATES PATENT OFFICE.

MABEL M. VAN VECHTEN, OF NEW YORK, N. Y.

SIDESADDLE.

No. 868,825.

Specification of Letters Patent.

Patented Oct. 22, 1907.

Application filed December 26, 1906. Serial No. 349,433.

To all whom it may concern:

Be it known that I, MABEL M. VAN VECHTEN, a citizen of the United States, and a resident of New York, in the county of New York and State of New York, 5 have invented certain new and useful Improvements in Sidesaddles, of which the following is a specification.

This invention relates to improvements in side-saddles, and the main object of the invention is to provide a toe-piece forming a resistance point against 10 which the right toe of the rider may press, and constituting substantially a reversed stirrup.

In side-saddles as heretofore constructed, there has been no provision for holding the right toe of the rider in a fixed position or for holding in such a manner as to 15 enable the rider to control her position in the saddle by upward pressure of the right toe against a resistance point. I have found that a better riding position, and a much more secure seat, can be maintained than with side-saddles of the ordinary type, in using which the 20 right foot is practically unsupported.

In ordinary side-saddles practically the whole weight of the rider is constantly thrown to the left or near side of the horse and saddle, and the pull of the saddle upon the horse's back is chiefly downward and to the left. This 25 pull is very much lessened in a side-saddle having a toe-piece of the character described for the right foot, as with such a device the right toe exerts a strong pull upward and to the right from the point of support of the underside of the right thigh on the saddle, especially 30 near the right knee.

One of the chief advantages resulting from this construction is that it is much easier to rise at the trot than is the case in using ordinary side-saddles, and one of the principal objects of this invention is to provide a saddle 35 in which the rise at the trot is made easy. When the right toe has a substantially fixed point to pull against it is easy to bring into full play the action of the right knee and to enable the rider to rise by swinging upward about the right knee joint as a fulcrum, this 40 motion being greatly assisted by the downward pressure of the under side of the right thigh against the saddle at a point close to the knee joint. Such an action as this is not possible when the right toe is swinging in the air, as in riding side-saddles of the ordinary type. Nor is it possible in an ordinary side-saddle 45 to avoid having the right leg pumped up and down in rising at the trot; whereas with the toe-piece employed by me a resistance point is provided which permits the rise at the trot to be effected by the straightening of the knee and the swinging of the right thigh and the body while the right leg below the knee is held immovable, it being impossible in the ordinary type of side-saddle to bring the muscles at the under side of the right thigh into action properly when the right leg below 50 the knee is left free to move up and down. When such a resistance point as that just described is pro-

vided for the right toe, it is also unnecessary for the rider to lean forward in rising at the trot, as she is obliged to do in rising in the ordinary side-saddle. With the leg firmly held below the knee the action of the knee 60 joint and thigh muscles is such that she can easily maintain an erect position and rise at the trot with much less effort than heretofore. Moreover, in turning to the left while trotting the rider's seat, in ordinary side-saddles, is very insecure, and the weight is carried 65 still further to the left than in trotting straight ahead, all of which increases the danger of falling off to the left. In my improved saddle, however, a much firmer seat may be had, and the weight thrown more to the right, by a pull to the right exerted by the rider in the 70 manner just described whenever her equilibrium is seriously disturbed.

With my improved device, for holding the right toe in toward the horse and against upward movement, side motion of the rider in rising at the trot is also prevented. 75 With such a device the unsightly moving projection ordinarily resulting from the sticking out of the right toe to the left and the moving up and down of the right leg below the knee disappears. A very square seat also results from the use of this device, and a much 80 stronger grip is obtained on the off crutch and on the near crutch or leaping-head than in the ordinary form of side-saddle.

While the chief advantage of my invention is that it renders it easy for a rider to rise at the trot, it is also 85 a valuable aid to the rider who desires to sit down in the saddle in trotting, as the jar upon such a rider is much less violent when the body is braced by the toe-piece than when the ordinary form of side-saddle is used.

Under all conditions of riding my invention assures 90 a stronger and better seat than it has been possible to obtain in side-saddles equipped with the ordinary crutches and the stirrup for the left foot. This is particularly true in moments of emergency, when a horse shies or otherwise misbehaves, especially when the rider 95 is in the act of rising in the saddle. At such a time the rider's seat with an ordinary side-saddle is very insecure, but in a saddle equipped with a toe-piece such as described the act of rising follows the gripping of the crutches and the pull on the toe-piece by the right foot, 100 and even if in the air, clear of the saddle, her grip on the crutches, toe-piece and saddle will be so strong that her seat will be secure.

In the drawings accompanying this specification and forming part of the application, Figure 1 is a side elevation of a saddle-tree having my invention applied thereto, the view being taken from the near side. Fig. 2 is a similar view, showing a rider in operative relation with the device applied to a side-saddle. Fig. 3 is a detail of the toe-piece proper, or reverse stirrup. Fig. 4 is a view similar to Fig. 2, illustrating a modification 110 of the invention, in which the toe-piece is attached

to the end of a strap fastened to the off side of the saddle, instead of being rigidly connected with the near point of the saddle-tree, as in the previous views. Fig. 5 is a full view of a horse and rider, the view being on a reduced scale, illustrating the attachment of such a loose toe-piece or reversed stirrup to the off side of the saddle. Fig. 6 is an enlarged detail of the toe-piece or reversed stirrup shown in Fig. 4.

Similar characters designate like parts in all the figures of the drawings.

My invention may be applied to a side-saddle in any manner whatever that will permit a toe-piece to be brought into position to be engaged by the upper side of the right toe of a side-saddle rider, and form a resistance point against which an upward pull may instantly be exerted by the right toe. Two different types of such device are shown in the drawings. Figs. 1 to 3 inclusive illustrate such a device, substantially rigidly connected to the near side of the saddle, preferably to the near point of the saddle-tree. The remaining views illustrate a device having the same function loosely attached to the end of a strap fastened, as by a buckle, to the off side of the saddle in such a manner that the upward pull thereon is transmitted directly to a point of connection, preferably high up on the off side of the saddle.

Referring first to the construction shown in Figs. 1 to 3 inclusive, 2 designates generally a saddle-tree of a side-saddle having the usual off crutch 3, near crutch 30 or leaping-head 4, and near point 5, the last of which forms an extension of the saddle-tree proper, and the first two of which project from the saddle-tree in the well-known manner. A device adapted to form a resistance point against which an upward pull may be exerted by the right toe is substantially rigidly connected with this saddle-tree. The resistance device shown is a curved rigid member, preferably of metal, and it is shaped to form substantially a reversed stirrup, that is to say, instead of being a point of resistance against which the under side or sole of the rider's foot will press, it is a point of resistance against which the upper side of the rider's toe may pull. This device is indicated herein by 6. It constitutes preferably an arched toe-piece conforming to the contour of the upper side 45 of the toe of a shoe, and will usually be padded, as indicated at 7; and covered to harmonize with the leather of the saddle proper. It is here shown as having a shank 8 perforated for the reception of a part to which it is to be attached, which in the constructions illustrated is a screw 9. A clamping-nut, such as 10, threaded onto the end of the screw 9, may hold the toe-piece in place in any desired angular position. This screw 9 is here threaded into the lower end of an angular support 11, illustrated as made of steel tubing internally 55 threaded at both ends. The screw 9 is threaded into the lower end of said support 11 and may be adjusted in position therein to regulate the height of the toe-piece. In a similar manner a screw 12 is here shown as threaded into the upper end of the tubular support 11 for the purpose of regulating the position of the toe-piece lengthwise of the saddle. This screw 12 is here fastened to a part attached to the near point 5 of a saddle-tree, the member to which it is attached being a bracket 13 having a screw-threaded lug 14 projecting therefrom into 60 which the screw 12 is threaded, a jam-nut 15 serving to

hold the screw 12 and hence the support 11 in the desired adjusted position. By means of the devices just described it will be seen that both vertical adjustment and adjustment lengthwise of the saddle may be had, so as to permit the location of the toe-piece 6 in the proper position for engagement by the right toe of a rider of any height, a few inches in each direction being a sufficient adjustment to accommodate riders of all the usual heights.

All of the other parts of the saddle are or may be of the conventional type found in side-saddles. The usual stirrup for the left foot is indicated at 16 attached by a strap 17 to the near side of the saddle in the well-known manner. The relative positions of the crutches, the stirrup for the left foot and toe-piece or reversed stirrup for the right foot, are indicated in Fig. 2, in which both of the stirrups are properly adjusted as to height to obtain the most perfect grip upon the crutches and saddle. With the parts so organized, with the left knee immediately below and slightly separated normally from the under side of the leaping-head 4, the pressure of the left knee may at any time instantly be brought against the leaping-head and pressure of the right toe against the toe-piece 6 and of the under side of the right thigh against the pommel of the saddle. The result of any pressure or upward pull against the under side of the toe-piece 6 and of simultaneous pressure of the under side of the thigh against the pommel of the saddle is that the saddle tends to pull toward the off side of the horse, which counteracts the normal tendency of the weight of the rider to draw the saddle down on the near side.

Figs. 4 to 6 inclusive illustrate an extremely simple type of the device, which may be used to advantage if permanent attachments to the saddle are not desired. It consists only of a strap fastened, as by a buckle, to the off side of the saddle, and a toe-piece of proper construction secured to the free end of the strap, this toe-piece being of any suitable type provided it embodies a resistance piece that will fit over the right toe and against which the right toe may pull. Here it is substantially a stirrup, and is indicated by 17. The working portion thereof is arched as before, and padded at 18. The strap by which it is connected to the off side of the saddle is shown at 19 and is adjustable to different heights 105 for different riders, if desired. This type of toe-piece accomplishes the same purpose as the other, but its proper use is dependent upon the possession of a good knowledge of riding, and sufficient skill in the use of the device to keep it in engagement with the toe. The other parts with which this reversed stirrup coats are the same in these views as in those previously described.

It will be seen that neither in the type of device shown in Figs. 1 to 3 inclusive nor in that shown in Figs. 4 to 6 inclusive is there any large and unsightly projection as a result of the presence of a device of this type. In the fixed type of device much of the attachment is covered either by the near flap 20 of the saddle or by the rider's boot, while in the other type of device there are no parts other than a strap and a small stirrup to which the strap is connected. In the main illustrative views, Figs. 2 and 4, such parts of the device as are in sight in those views will in actual use be covered entirely by the skirt of the rider, the skirt not being shown in these

views, as it would prevent a proper illustration of the parts.

What I claim is:

1. The combination with a side-saddle having a stirrup for the left foot, of a toe-piece secured to the saddle and located when in use at the near side thereof above and in advance of said stirrup and in position to be engaged by the right toe of the rider and resist upward movement thereof.
2. The combination with a side-saddle having a stirrup for the left foot, of an adjustable toe-piece secured to the saddle and located when in use at the near side thereof above and in advance of said stirrup and in position to be engaged by the right toe of the rider and resist upward movement thereof.
3. The combination with a side-saddle having a stirrup for the left foot, of a vertically-adjustable toe-piece secured to the saddle and located when in use at the near side thereof above and in advance of said stirrup and in position to be engaged by the right toe of the rider and resist upward movement thereof.
4. The combination with a side-saddle having a stirrup for the left foot, of a toe-piece secured to the saddle and adjustable vertically and also lengthwise thereof and located when in use at the near side of the saddle above and in advance of said stirrup and in position to be engaged by the right toe of the rider and resist upward movement thereof.
5. The combination with a side-saddle having a stirrup for the left foot and also having an off crutch and a leaping-head, of a toe-piece secured to the saddle and located when in use at the near side thereof between and in advance of the leaping-head and said stirrup and in position to be engaged by the right toe of the rider and resist upward movement thereof.
6. The combination with a side-saddle having a stirrup for the left foot, of a toe-piece secured to the near point

of the saddle-tree and located above and in advance of said stirrup and in position to be engaged by the right toe of the rider and resist upward movement thereof.

40

7. The combination with a side-saddle having a stirrup for the left foot, of a toe-piece secured to the near point of the saddle-tree and located above and in advance of said stirrup and adjustable in position with respect to said point and in position to be engaged by the right toe of the rider and resist upward movement thereof.

45

8. The combination with a side-saddle having a stirrup for the left foot, of a toe-piece secured to the near point of the saddle-tree and located above and in advance of said stirrup and adjustable relatively to said point both vertically and lengthwise of the saddle-tree and in position to be engaged by the right toe of the rider and resist upward movement thereof.

50

9. The combination with a side-saddle having a stirrup for the left foot, of a support attached to the near point of the saddle-tree and adjustable relatively thereto lengthwise of said saddle-tree, and a toe-piece secured to the free end of said support and located above and in advance of said stirrup and in position to be engaged by the right toe of the rider and resist upward movement thereof.

55

10. The combination with a side-saddle having a stirrup for the left foot, of a support attached to the near point of the saddle-tree and adjustable relatively thereto lengthwise of said saddle-tree, and a toe-piece secured to the free end of said support and located above and in advance of said stirrup and adjustable thereto vertically of the saddle-tree and in position to be engaged by the right toe of the rider and resist upward movement thereof.

60

Signed at New York in the county of New York, and State of New York, this 24th day of December, A. D. 1996. 70

MABEL M. VAN VECHTEN.
